(57) **CLAIM**

The ornamental design for a nasal air filter, as shown and described.

DESCRIPTION

FIG. 1 is a front elevation view of a nasal air filter showing our new design;

FIG. 2 is a side elevation view;

FIG. 3 is a top plan view;

FIG. 4 is a bottom plan view; and,

FIG. 5 is an isometric view of a nasal air filter showing our new design.

The dotted lines showing an exemplary user's nose is for illustration only and forms no part of the claimed design.
